(57) **CLAIM**

The ornamental design for a steering handle grip, as shown and described.

DESCRIPTION

FIG. 1 is a perspective top front right view of a steering handle grip, showing my new design;

FIG. 2 is a perspective top rear left right view thereof;

FIG. 3 is a front elevation view thereof;

FIG. 4 is a rear elevation view thereof;

FIG. 5 is a left elevation view thereof;

FIG. 6 is a right elevation view thereof;

FIG. 7 is a top plan view thereof; and,

FIG. 8 is a bottom plan view thereof.

The broken lines shown represent portions of the steering handle grip that form no part of the claimed design.
